UNITED STATES PATENT OFFICE.

JOHN HENRY THOMAS, OF JOHANNESBURG, TRANSVAAL.

DRILL FOR DRILLING HOLES IN ROCK OR THE LIKE.

No. 821,202.

Specification of Letters Patent.

Patented May 22, 1906.

Application filed November 14, 1904. Serial No. 232,656.

To all whom it may concern:

Be it known that I, JOHN HENRY THOMAS, a subject of the King of England, residing at Johannesburg, in the Colony of the Transvaal, have invented certain new and useful Improvements in Drills for Drilling Holes in Rock or the Like, (for which I have made application for patent in the Transvaal, No. 293, filed July 20, 1904,) of which the following is a specification.

The present invention is applicable to the drills or bits employed for drilling holes in rock and the like in mining, quarrying, and similar operations. It may be utilized in the production of such tools either for hand or machine drilling.

The improvements relate particularly to the kind of drill or tool which is provided with detachable and renewable bits or cutters.

The object of the invention is to provide efficient means for attaching the renewable bits or cutters onto their "steels" or "shanks" and to permit said cutters to be detached from their shanks and renewed with greater facility than is possible with existing constructions of such devices. The bits and shanks are of simple design, easy of manufacture, and can consequently be produced at a comparatively small cost.

I will now proceed to describe my invention in detail by aid of the accompanying sheet of drawings, wherein by way of example I illustrate the same applied in the construction of a "chisel" bit or tool formed with one transverse cutting edge.

In the drawings, Figure 1 represents an elevation of a portion of the drill steel or shank with the detachable cutter fixed therein. Fig. 2 is an elevation at right angles to Fig. 1. Fig. 3 is an elevation of the shank or steel with the cutter removed. Fig. 4 is a plan of Fig. 3. Fig. 5 is a side elevation of the cutter detached. Fig. 6 is an end elevation of Fig. 5. Fig. 7 is a plan of the detached cutter as seen from the under side. Fig. 8 is a perspective view of the detached cutter.

In the drawings, 1 represents the drill or steel, and 2 the detachable and renewable bit or cutter. The steel 1 is, as shown, preferably beveled off on two opposite sides 3 4 for a portion of its length in the direction of the detachable cutter 2, and it is preferably rounded off between said beveled faces 3 4,

as is indicated at 5 in Figs. 1 and 3. Across the end of the steel 1 is formed a transverse slot 6, which slot is rounded or curved at the bottom, as indicated at 7, and beveled inward and upward, as seen at 8, from the shoulders or projections 8, formed at the top of the rounded portion 7, to the end of the drill or steel 1. The slot 6 is also made taper or wedge shape transversely of the steel 1, as is illustrated more particularly in Figs. 1, 3, 6 and 4.

The end of the steel 1 between the slot 6 and the rounded edges 5 is beveled off from the center, as seen at 9 in Figs. 1 and 3.

The bit 2 in its upper portion is formed of 70 triangular or substantially triangular section, which forms upon it the cutting edge 10. The cutting edge 10 is sufficiently long to afford proper clearance for the steel 1 as the drill or bit penetrates the rock. The sides 11 of the 75 triangular portion are shaped on the under side to fit the beveled parts 9 of the steel 1. That portion of the cutter or bit 2 which is fitted in the slot 6 of the steel 1 is constructed of bulbiform cross-section corresponding to 80 the shape of the slot 6—that is to say, it is fashioned with a bulbous or rounded and tapered lower portion 12, corresponding to the rounded bottom portion 7 of the steel 6 and with a beveled upper part 13, which is made 85 taper or wedge shape, as is clearly illustrated in Fig. 6, to correspond to the bevel 8 of the upper portion of the transverse slot 6.

In attaching the cutter 2 to the steel 1 the smaller end of the bulbiform projection 12 is 90 inserted in the larger end of the transverse slot 6 and the cutter 2 then projected transversely across the end of the steel 1 until the projection 12 13 tightly fits the slot 6. The cutter 2 is detached by moving it in the opposite direction—as, for example, by tapping it with a hammer or otherwise.

What I claim as my invention, and desire to protect by Letters Patent, is—

In a drill for drilling holes in rock and the like, in combination, the steel 1 beveled off on two opposite sides 3, 4, and formed with a transverse slot 6, rounded at the bottom 7 and beveled inward and upward to the top of the slot and tapered transversely, the end of 105 the steel being beveled upwardly from the sides 5 to the edges of the slot, the cutter 2 shaped on the under side to fit the beveled end of the steel 1 and formed with a projection 12, 13 corresponding to the transverse 110

slot 6 formed in the end of the steel 1, said cutter having its cutting edge of a greater length than the distance between the sides 3 and 4 of the steel 1, the width of said cutter being substantially the same as the diameter of the steel at right angles to the slot therein.

In witness whereof I have hereunto set my

hand in the presence of two subscribing witnesses.

JOHN HENRY THOMAS.
